UNITED STATES PATENT OFFICE.

THOMAS GASKELL ALLEN, OF WESTMINSTER, LONDON, ENGLAND.

ACETYLENE-GAS GENERATOR.

1,079,972.

Specification of Letters Patent.

Patented Dec. 2, 1913.

Application filed December 5, 1911. Serial No. 664,025.

To all whom it may concern:

Be it known that I, THOMAS GASKELL ALLEN, of 106 Victoria street, Westminster, London, England, engineer, have invented 5 certain new and useful Improvements in or Relating to Acetylene-Gas Generators, of which the following is a specification.

This invention relates to acetylene gas generators of the automatic type wherein a 10 predetermined pressure of gas in the generating chamber acts upon the water supply to regulate the admission of water according to the requirements.

The invention is obviously applicable for 15 use in the generation of gases other than acetylene where liquid is added to material in the generating chamber for producing the gas. The invention will, however, be hereinafter described with reference to acetylene, the other uses being held to be included.

The object of the present invention is to provide an improved construction of that 20 type of generator or water feeding device described in my prior Patent No. 997,944.

The invention is particularly applicable to small generators, such as those employed for lighting vehicles or for portable and domestic use, although the invention may 25 be applied to larger plant.

According to this invention I provide for or in combination with the generating chambers of acetylene generators of the automatic type, a water feeding device consisting of flat surfaces lying in parallel planes or a plurality of members having flat surfaces, brought and held together in such close contact that the water can only seep or ooze between them under water head or 30 other pressure, said surface or surfaces being of such dimensions as to provide an extended inlet to insure a sufficient aggregate of water feed and as to provide an extended closure between the intake and discharge to hold a sealing film of water 35 against the back pressure of the gas under normal working conditions. A water feeding device thus constructed will permit a sufficient volume of water to pass for the 40 purposes of generation, but in such slowly moving and limited quantities at any given point that an immediate and exact regulation of the water feed is effected by the slightest tendency to back pressure, without any appreciable disturbance being 45 caused in the equilibrium between the op-

posing internal and external pressures. Evenness of generation and a uniform pressure at the burner are thereby insured. Such water feeding device holding a sealing film of water as described also serves to prevent the escape of the gas while permitting the requisite amount of water to feed in. This sealing film of water is also very useful when it is desired to discontinue the generation of gas. The apparatus may then be withdrawn from the water, thereby stopping the water feed, whereupon the water film will continue to oppose the escape of gas through the inlet although the water 50 head has been removed by such withdrawal, and the gas will continue to pass through the burner until the after make is exhausted. The invention also gives facility for obtaining the different pressures which may be 55 required by different burners or different apparatus merely by increasing or decreasing the depth at which the water feeding device is immersed. The substantially high pressure required for a flare light may be 60 readily obtained by increasing the head of water to which the water feeding device is subject, a simple means to this end being the provision of a water tank of suitable depth. Further means may be provided for 65 adjusting the position of the generating chamber to compensate for the diminished head of water when a narrow water receptacle is employed.

The apparatus or that part of it which 70 constitutes the generating chamber may be of any suitable shape or size.

The accompanying drawings illustrate a 75 number of constructions made in accordance with this invention.

Figure 1 is a vertical section; and Fig. 2 is a plan of the improved generator; Fig. 3 is a perspective view, partly in section, of another construction; Fig. 4 is a plan of Fig. 3 in section; Fig. 5 is a sectional perspective view of a modified construction; Fig. 6 is a vertical section of another modification; and Fig. 7 is a sectional perspective view of a further modified construction. Fig. 8 is a view of a generator seated with 80 its water container applied as a table lamp.

In the construction shown in Figs. 1 and 2 the generating chamber consists of a carbid receptacle *a* and a cover *b*. These two 85 parts are joined by flanges *c* and *d* which constitute both the water feeding device

and the closure for the generating chamber. The flanges *c* and *d* are clamped together by means of a bridge piece *e* controlled by a winged nut *f*; the ends of the bridge piece are bent to the shape of a claw bearing on the underside of the flange *c* as at *g* so that by rotation of the nut the bridge piece is raised and the cover *b* pressed down thereby clamping the adjacent surfaces of the flanges *c* and *d* together. In the construction shown the gas pipe *h* is screwed directly into the top of the cover *b* and the winged nut *f* is mounted so as to rotate upon the end of the pipe. Suitable stops *j* will be provided on the inside of the cover to properly centralize the same and guiding flanges *k* will be provided on the outside of the cover to insure that the bridge piece *e* is correctly placed in position. In operation the generator is immersed in water to such a depth that the head of water above the same will cause the water to seep or ooze between the contacting flat surfaces of the flanges *c* and *d* and so pass into the generating chamber *a*. The pressure of generated gas reacting on the oozing discharge of water will automatically maintain the required balance between the water oozing in and the demand for gas by the burner or burners whereby a steady generation of gas and a steady flame are maintained. The flanges *c* and *d* are of the required dimension to give the automatic water feeding and closure effects referred to. For example, the circumference of the flanges is such as to provide the extended inlet for water between them and the width between the inner and outer edges of the flanges insures that the contacting surfaces will hold a sealing film of water against the back pressure of the gas under normal working conditions.

In the construction shown in Figs. 3 and 4 the water feeding device consists of two flat surfaced disks *c* and *d* inclosing between them a number of intermediate disks *o*, all the said disks are pierced in the middle with coincident holes *p* which form a through passage for the water from the disks to the carbid chamber, which is suitably connected to the lower disk *d*. Any suitable means may be provided for clamping or holding the disks together and in contact the one with the other. In the construction illustrated in Fig. 3 this is accomplished by fixing to the upper disk a gas pipe *h* which leads to the burner or burners, the lower end of the pipe *h* is adapted to screw into the hole in the lower disk *d* and thereby serve as a means for drawing and holding the whole of the disks tightly together. The screw thread on the gas pipe *h* is mutilated to provide longitudinal channels or passages *h'* by which the water oozing out from between the disks may pass down into the

generating chamber where it is directed to the side of the chamber by means of a distributing plate *h''* which acts to prevent the water from accumulating and falling in large drops. The holes in the intermediate disks *o* and the end disk *d* may be square or otherwise so shaped as not to interfere with the passage of the water along the channels *h'*. In this construction the generating chamber is closed in any suitable manner apart from the water feeding device and obviously the gas may if required be led away by a pipe entirely separate from the water feeding device. The operation is similar to that given for Figs. 1 and 2. The water in this case seeps or oozes between the contacting flat surfaces of the disks *c*, *d* and *o*, and so passes into the central aperture and down by the channels *h'* into the generating chamber. The pressure of generated gas reacts on the oozing discharge of water, as before described. The disks *c*, *d* and *o* are of the required dimensions to give the automatic water feeding and controlling effects referred to, for example, the circumference of the disks is such as to provide the extended inlet for the water between the disks, and the distance of the central holes from the periphery insures that the contacting surfaces of the disks will hold a sealing film of water against the back pressure of the gas under normal working conditions. In Fig. 3 a number of disks *o* are shown clamped between the disks *c* and *d*, and as the number of these disks is increased or lessened, so the capacity of the water feed is increased or lessened, and in some cases where the demand on the generator is limited, the intermediate disks *o* may be omitted, the disks *c* and *d* being clamped one against the other. In Fig. 3 the water enters between the disks by the outer edge and oozes out at the central aperture. This arrangement may however be reversed as shown in Fig. 5 where the water enters at the central hole and discharges around the edge of the disks into the carbid chamber. In this figure the intermediate disks are omitted. The operation is as already described.

Fig. 6 shows a construction where the water feeding device consists of three disks *c*, *d* and *o* disposed at the base of the generating chamber. The said disks are clamped together in suitable manner as by wing nuts and bolts *i*. Only the two upper disks are pierced with holes *o'*. The operation is as before described except that the water oozes into the bottom of the vessel and attacks the carbid upwardly. The gas is led away from the top by a pipe *h*. A deflecting plate *m* may be provided if required to direct to the side of the chamber any condensation from the gas in the outlet pipe *h*.

Should it be required to provide a water

feeding device adapted to be put out of action by other means than removal from the water or by closing the gas pipe, then this can be accomplished as shown for example 5 in Fig. 7, by employing two disks *c* and *d* clamped together by the aid of a screw device adapted to be partly rotated by turning around the upper or burner carrying part *q*. The surfaces of the flanged members *c* and *d* will be machined or polished so that by rotating the burner part *q* and thereby clamping the disks tightly together such a tight joint will be secured that no water 10 can pass, while by a part rotation of the part *q* in the opposite direction, preferably determined accurately by a slot and stop pin such as *q'*, the surfaces of the disks may be moved such a minute distance apart as will enable them to operate as a water feeding 15 device and closure in the manner hereinbefore described.

If required, as for example in the case of a large plant, I may provide a number of generating chambers such as described, 20 adapted to be immersed in a suitable tank and suitably connected to the discharge or storage gasometer or the like.

Heretofore in this specification it has been stated that the surfaces constituting the water feeding device are adapted to be brought 25 and held together in such close contact that the water can only seep or ooze into the generating chamber under a pressure of water head. Such holding together causes a 30 contact between the said surfaces as follows, to wit: In the employment of ordinary metal surfaces produced by rolling or stamping, a contact between them will be in such a relation as will cause the said surfaces 35 to touch at innumerable points and to become in apposition at all points without sensible intervening space but still permitting water to seep or ooze through such spaces under pressure of water head or its equivalent, due to the slight inequalities of the 40 surface so produced. Obviously the extended inlet having this minute thickness may be provided by other means than those de-

scribed, within the limits of the appended claims, for example machined or polished 50 surfaces may be brought into such close relation as to produce an equivalent effect. Further the water feeding pressure may be obtained or supplemented by other means than water head, such as pressure of air or 55 other fluid, upon the water.

It is to be understood that the flat surfaces of the water feeding device may be disposed in other than horizontal positions, for example, they may be in vertical or inclined 60 positions.

What I claim and desire to secure by Letters Patent is:—

1. An acetylene generator comprising a generator chamber, a water feed device, and means for subjecting said water feed device to water pressure, said water feed device comprising flat surfaces in contact and pressed together constituting a restricted water inlet between them, the line of outermost contact of the flat surfaces when the device is in use being directly exposed to the body of water in which the device is submerged. 70

2. An acetylene generator comprising a generator chamber, a water feed device, and means for subjecting said water feed device to water pressure, said water feed device comprising flat surfaces having an aperture in their mid-area constituting a restricted water inlet between them, one end of said aperture leading to a burner, and the other side of said aperture communicating with the generating chamber, the line of outermost contact of the flat surfaces when the device is in use being directly exposed to the body of water in which the device is submerged. 80

In witness whereof, I have hereunto signed my name in the presence of two subscribing witnesses. 85
